TEMPERATURE CONTROL FOR COOLING
INTERNAL-COMBUSTION ENGINESElmore J. Sanders, San Gabriel, Calif., assignor
to Evans Products Company, Plymouth, Mich.,
a corporation of Delaware

Application July 21, 1947, Serial No. 762,405

5 Claims. (Cl. 123—12)

1

This invention relates to temperature control for cooling an internal combustion engine equipped with variable pitch fan blade assemblies which vary the volume of air supplied for cooling purposes, and an object is to produce a simple and efficient mechanism for supplying fluid under pressure to control the pitch of the fan blades, and thermostatically regulating the effectiveness of the fluid.

Another object is to control the operation of a variable pitch fan used for engine cooling purposes by means of liquid under pressure, such as oil from the engine crank case, and regulate the pressure created by such liquid by thermostatic means responsive, for example, to the temperature of the engine cooling liquid.

These and other objects and advantages of this invention will hereinafter appear, and for purposes of illustration but not of limitation, an embodiment of the invention is shown in the accompanying drawings, in which

Figure 1 is a schematic view partially in section of a portion of an internal combustion engine mounting the parts illustrative of the invention; and

Figure 2 is a fragmentary sectional elevational view partially in section of the variable pitch fan blade assembly with a portion of the fan blade adjusting means mounted on the front thereof.

This invention contemplates the use of a mechanism for adjusting the pitch of the fan blades of a variable pitch fan blade assembly of the type described in my United States Patent No. 2,437,810, granted March 16, 1948, and entitled "Variable Pitch Fan Blade Assembly." The mechanism includes fan blade pitch controlling means responsive to pressure fluid and separate means regulated in accordance with the engine temperature, such as the temperature of the cooling liquid, to regulate or control the effectiveness of the pressure fluid. Thus, the pitch of the fan blades may be varied in accordance with the temperature of the cooling liquid.

In specific application, positive results have been achieved when the pressure fluid is hydraulic fluid circulated at relatively constant pressure by the oil pump of the engine, but suitable fluid pressure may be developed from other sources, such as by the application of atmospheric pressure against the intake manifold vacuum.

Referring now to the drawings, 10 indicates the forward end portion of the motor block of an

2

internal combustion engine having a jacket 11 through which cooling liquid 12, such as water, is able to flow. A rotatably mounted stub shaft 13 extends forwardly of the motor block and is driven by means of a grooved pulley 14 connected by a belt 15 to an engine drive shaft (not shown). Mounted on the end of the shaft 13 is a variable pitch fan blade assembly F constituted generally of a series of fan blades 16 extending radially from a hub portion H.

The variable pitch fan blade assembly F is fully described in my co-pending application previously pointed out, and detailed description thereof is considered unnecessary except as to the manner in which the regulating mechanism operates with the fan blade assembly for varying the pitch of the fan blades. Suffice it to say that the fan blade assembly comprises a multiplicity of radially extending fan blades 16 which are counterweighted constantly to urge the fan blades to go into pitch during the operation of the fan. Each of the fan blades carries a stub shaft formed of successive sections of large and small diameter 17 and 18 respectively. The shaft section 18 of smaller diameter is mounted between ball bearings 19 housed within a flanged cup-shaped member 20 that seats in an annularly recessed portion 21 formed in the split sections 22 and 22a that comprise the hub H, which sections are joined together by bolt means (not shown).

Each stub shaft 18 has a depending screw-threaded portion 23 threadably engaged by a jack nut 24 which supports the roller bearing 19. By turning the nut, a depending pin 25 is withdrawn from an aperture 26 through a disc member 27 rotative in the area between the split hub sections 22 and 22a. When properly assembled, transverse apertures in the pin 25 and the disc 27 are in registry so that a key 28 may be inserted therethrough to maintain the parts in their assembled relation. Each disc 27 carries a pin 29, which is offset from the center of the disc and seats in an aperture 30 formed in the outer or peripheral wall of an actuating sleeve 31. The rearward wall of the sleeve 31 is formed with an annular groove 32 having a substantially perpendicular outer side wall 22 and a sloping inner side wall 34, while the forward wall of the sleeve is also recessed, as at 35, to provide space in which part of the sleeve actuating means, hereinafter to be described, may be positioned to provide for a more compact unit.

Responsive to the longitudinal movement of the actuating sleeve 31, the elements described

cooperate to effect the rotative adjusting movements of the fan blades in one direction or the other relative to the supporting hub member. Movement of the actuating sleeve in the forward direction is constantly urged by a coil spring 36, which is conically shaped in longitudinal section with the end portion thereof of larger diameter seating within the annular groove 32, while the other smaller end portion of the spring bears against a wall which may form a part of, or is fixed to, the end of the stub shaft 13. Longitudinal movement of the sleeve in the rearward direction may be effected by means of a horizontally disposed shaft 37 having a threaded end portion 38 which mounts a sleeve 39. The sleeve 39 is provided with an annular flange 40 at the forward end thereof which engages the forward wall of anti-friction bearings 41 that separate the sleeve 39 from the actuating sleeve 31. The latter sleeve is provided with an inwardly extending shoulder 42 for engaging the rearward wall of the bearings 41. Thus relative rotational movement between the actuating sleeve and the shaft 37 is permitted, while longitudinal movement of the shaft 37 provides for corresponding movements of the actuating sleeve.

The shaft 37 is adapted to be shifted in one direction or the other by means of an actuating device A stationarily supported on the front of the hub section H. For purposes of mounting the device, there is provided a bracket in the form of a disc plate 43 having an outwardly extending annular flange 44 with a number of apertures therein and a central apertured portion 45 through which the shaft 37 extends. The bracket 43 is fixed, as by brazing, to the forward open end of a sleeve 46 which is closed at the other end by a wall 47 having a central aperture through which the shaft 37 slidably extends. Additional support for the shaft 37 may be provided by an adaptor 48 which is screw-threaded on its outer wall threadably to engage the inner wall of the sleeve 46 in which it is disposed. The adaptor 48 is closed at its forward end by a wall 49 having an aperture through which the shaft slidably extends, and it is provided with a fluid packing 50 which encases that portion of the shaft 37 that is disposed within the adaptor.

In order to enable relative rotational movement between the hub section H and the bracket 43 and, at the same time, to provide for sufficient support, anti-friction means 51 are interposed between a horizontally disposed sleeve section 52 forming the central part of the hub section 22 and the sleeve 46. The sleeve section 52 has an inturned annular flange 53 at the forward end thereof for preventing relative forward movement of the anti-friction means 51, rearward relative movement thereof being prevented by means of a stop nut 54 threadably engaging the threaded end portion of the sleeve 46.

The shaft actuating device A is formed of a rigid housing 55, the rearward wall of which is provided with outwardly extending flanges 56 having apertures therein, which may be placed in registry with the openings in the flange 44. The housing 55 may then be held in this position by bolt and nut means 57 insertable through the registered openings. Separating the chamber within the housing into forward and rearward compartments 58 and 59 respectively, is a movable wall, which in the preferred embodiment, consists of a vertically disposed diaphragm 60 of

resilient material having the edge portions thereof secured in sealing relation between the housing wall, but may equally be in the form of a piston reciprocal within the chamber. To enable the desired movement of the diaphragm 60, that portion disposed within the housing is adapted to be larger than that of the cross sectional area of the compartment in which it is disposed. As a result, the central portion of the diaphragm is shiftable longitudinally relative to the housing to a limited extent.

Engaging the rearward wall of the diaphragm is a rigid plate 61 secured to the end of the shaft 37. The plate and shaft is constantly urged in the forward direction by a coil spring 62 interposed between the plate and the rearward housing wall 63 and supplemented by the forces developed by the coil spring 36. These spring forces supplement the centrifugal torsion developed by the counterweights on the fan blades for causing the fan blades to move into pitch, and they operate alone for such purpose when the speed of the engine is such that sufficient centrifugal torsion is not made available. Rearward displacement of the shaft against the forces developed by the coil springs and the counterbalancing means results from other forces acting on the opposite face of the diaphragm. For this purpose, use is made of pressure fluid delivered by the fluid pump which forms a part of most engines. The pressure fluid enters and leaves the compartment 58 through the port 64 connected by a tubular passage 65 with the fluid pump. Instead of the coil spring 62, pressure fluid may be used for causing movement of the diaphragm and shaft in the direction to cause the fan blades to go into pitch. In such instances, a coil spring or other biasing or pressure fluid means may be employed in the other chamber for effecting the translatory shifting movement of the diaphragm and shaft in one direction or the other for controlling the pitch of the fan blades.

For regulating the fluid pressure within the chamber, or the flow of fluid to and from the actuating device, there is interposed between the fluid pump and the actuating device A, a pressure fluid regulating means B consisting generally of a by-pass for the liquid under pressure, and valve means responsive to the temperature of the cooling liquid for regulating the flow of liquids through the by-pass. More specifically, the fluid regulating means comprises a cylindrical housing 66 positioned upright on the motor block 10, the lower end portion of the housing being screw-threaded at 67 for enabling threaded engagement with a threaded aperture 68 through the upper wall 69 of the water jacket 11. The housing is divided into an upper chamber 70 and a lower chamber 71 by means of a horizontally disposed wall 72 having an aperture 73 through the center thereof. That portion of the wall bounding the upper portion of the aperture 73 is tapered outwardly at an angle corresponding to the slope of a frustum shaped valve member 74 shiftable vertically through the opening 73. When the lower portion of the member 74 of small cross section is disposed within the opening 73, a relatively large annular space remains about the member for enabling ready communication between the chambers 71 and 70, but when the member 74 is shifted in the downward direction, the space becomes more restricted until communication between the chambers is entirely cut off. This occurs when the tapered side wall

of the frusto-conical member 74 seats in the aperture, with the engaging tapered portions providing for a greater area of engagement. The member 74 is guided in vertical shifting movement by a pin 75 secured to the upper wall thereof and shiftable within a concentric opening 76 in the upper wall of the housing, and by another pin 77 depending from the lower wall thereof and shiftable through an aperture 78 in a bushing 79 that threadably engages a threaded opening 80 through the lower wall of the housing 66.

Vertical shifting movement is imparted to the pin 77 and consequently the member 74, by means of a thermostat 81 disposed in the fluid stream of a water jacket 11. Thermostats of the type to impart vertical shifting movement in response to temperature changes are commercially available, such, for example, as the unit marketed under the designation "Vernatherm," and since the thermostat itself forms no part of this invention, detail description thereof is considered unnecessary. Suffice it to say that responsive to increases in the cooling liquid temperature, the frustum member 74 is shifted upwardly, and it is shifted in the opposite direction in response to reductions in the cooling liquid temperature.

Oil or other fluid is delivered under relatively constant pressure from the outlet of a fluid pump (not shown), through a tubular passage 82 to the inlet port 83 forming a part of a side arm passage 84 leading to the chamber 71. Interposed between the port 83 and the chamber 71 is a restriction in the form of an apertured sleeve 85 for reducing the amount of fluid that is able to pass into the chamber 71. The fluid by-passed from the lower chamber 71 into the upper chamber 70 through the annular opening about the frustum member 74 is returned to the fluid supply or sump through a side arm passage 86 having an outlet port 87 connected by a tubular passage 88 to the sump (not shown). Another side arm passage 89 leading from the lower chamber 71 is in communication with the tubular passage 65.

In normal operation, the several fan blades 16 are thrown into a predetermined pitch by the counterbalancing means described. Thereafter the means described function automatically further to increase or to decrease the pitch of the fan blades and correspondingly the volume of the cooling air directed by the fan blades to the radiator or to the engine in accordance with the increase or decrease of the temperature of the cooling liquid. In this manner, not only is the temperature of the cooling liquid maintained within a narrow temperature range but the power requirements for operating the fan assembly are at a minimum because, when the cooling water is at a low temperature, practically no power is expended in actuating the fan blades.

In normal operation, pressure fluid circulates from the fluid pump into the lower chamber 71, thence through the by-pass or aperture 73 and into the upper chamber, from which it is returned to the fluid source. Because of the restriction between the two chambers, a pressure differential between the fluids therein may be made to exist, and the pressure differential may be varied in accordance with the position of the frusto-conical member 74 or valve which regulates the opening between the chambers in the manner described. For example, as the temperature of the cooling liquid decreases, the valve member 74 is shifted downwardly further to restrict the annular space or by-pass opening between the cham-

bers with the result that higher fluid pressures are built up within the lower chamber, and as the temperature of the cooling fluid 12 increases, the thermostat shifts the valve member 74 upwardly to provide for a larger by-pass with a proportionate reduction in pressure.

The pressure in the lower chamber 71 has a direct affect on the flow of the pressure fluids to the chamber 58. When the fluid pressure therein is increased, as when the member 74 shifts downwardly further to restrict the opening, pressure fluid flows to the chamber 58, causing the diaphragm 60 and the shaft 37 to shift rearwardly against the forces of the springs and the counterbalance to reduce the pitch of the fan blades. Thus the air flow and concomitantly the power requirements for operating the fan are reduced. When the frustum 74 is shifted upwardly in response to an increase in the temperature of the cooling liquid, the fluid pressure within the lower chamber is proportionately reduced, and the forces operating to increase the pitch of the fan blades force some of the pressure fluid back into the circulation with the result that the shaft may be shifted forwardly and the pitch of the fan blades is increased so that a greater volume of air is directed to the radiator or the engine.

A cardinal feature of this invention resides in the association of parts which provides for a simple and constantly operating means for automatically and smoothly varying the pitch of the several fan blades of a variable pitch fan blade assembly in accordance with the temperature of the engine, and although the embodiment of the invention is that of a liquid-cooled engine, the invention is not to be regarded as so limited, because it can advantageously be embodied in an air-cooled engine in which a thermostat may be in metal to metal contact with the cylinder head, for example. In the illustrated embodiment, a fluid, such as oil from the crank case, is circulated under pressure by the usual oil pump and is delivered at substantially constant pressure to a valve means thermostatically controlled from the cooling liquid for regulating the flow of the oil, and a fluid actuated means is provided for effecting the regulation of the pitch of the fan blades responsive to the pressure of the oil. An important concept is the utilization of a fluid for fan pitch controlling purposes, and although oil from the engine crank case is hereby specifically described, it is to be understood that gaseous fluids, such as subatmospheric pressure fluid operating in opposition to gas at atmospheric pressure, may be employed to advantage.

The thermostatically controlled fluid valve may be positioned to function in cooperation with any part of the engine for regulating the pitch of the fan blades in accordance with the temperature of the engine in a specified region. The fan blade actuating means may be positioned any distance from the fluid regulating valve; it may be positioned on the front of the fan assembly and immediately to the rear of the radiator; it may be positioned on the rear of the fan assembly, which it may actuate, as a result, by means of a pusher rod; or it may be offset from the fan assembly with which it may be operatively connected by means of suitable lever rods. Together the thermostatically controlled valve and the actuating device comprise parts which are simple to manufacture and assemble on a mass production basis and together they form a constantly operating system which requires little repair or

adjustment automatically to effect the desired regulation.

It is to be understood that numerous changes in the details of construction, arrangement and operation of various parts may be effected without departing from the spirit of the invention especially as defined in the appended claims.

What I claim is:

1. In a liquid cooled internal combustion engine equipped with a variable pitch fan blade assembly adapted to supply air for engine cooling purposes, means responsive to the temperature of the cooling liquid for varying the pitch of the fan blades, said means comprising a chamber having a movable wall operatively connected to the fan blade assembly, a source of fluid under pressure, said source and fluid being inherent operatively to the engine and in communication with said chamber, and means responsive to the temperature of the engine cooling liquid to regulate the fluid in said chamber to vary the pitch of the fan blades.

2. In an internal combustion engine equipped with a variable pitch fan blade assembly adapted to supply air for engine cooling purposes, means responsive to the temperature of the engine for varying the pitch of the fan blades, said means comprising an expansible chamber motor having a movable wall operatively connected to the fan blade assembly, a source of fluid under pressure, said source and fluid being inherent operatively to the engine and in communication with said chamber to actuate said motor in one direction, biasing means independent of said motor to actuate said motor in the other direction, and valve means thermostatically responsive to the temperature of the engine for regulating the pressure of the fluid in said chamber to vary the pitch of the fan blades.

3. In an internal combustion engine equipped with a variable pitch fan blade assembly adapted to supply air for engine cooling purposes, means responsive to the temperature of the engine for varying the pitch of the fan blades, said means comprising a chamber, a diaphragm separating the chamber into two compartments and having a portion thereof movable within the chamber and operatively connected to the fan blade assembly, a source of fluid under pressure, said source and fluid being inherent operatively to the engine and in communication with at least one of said compartments, and valve means responsive to the temperature of the engine for regulating the pressure of the fluid in communication with said compartment and thus varying the pitch of the fan blades.

4. In a liquid cooled internal combustion engine equipped with a variable pitch fan blade assembly adapted to supply air for engine cooling purposes, means responsive to the temperature of the cooling liquid for varying the pitch of the fan blades, said means comprising an expansible chamber motor having a movable wall operatively connected to the fan blade assembly for effecting fan blade adjustments, a source of pressure fluid, said source and fluid being inherent operatively to the engine and in communication with said chamber, a valve member regulating the fluid in said chamber and thermostatic means disposed within the cooling liquid actuating said valve member in accordance with the temperature of the cooling liquid thereby to vary the pitch of the fan blades.

5. In an internal combustion engine equipped with a variable pitch fan blade assembly adapted to supply air for engine cooling purposes, means responsive to the temperature of the engine for varying the pitch of the fan blades, said means comprising a chamber having a movable wall operatively connected to the fan blade assembly for effecting fan blade adjustments, a source of pressure fluid in communication with said chamber, a housing interposed between the pressure fluid source and said chamber, a wall in said housing having an aperture through which the pressure may be by-passed to the fluid source, a shiftable valve member cooperating with said aperture for regulating the flow of the pressure fluid through said by-pass, and means movable in response to changes in the engine temperature and operatively connected to shift said valve member thereby to vary the flow of pressure fluid through the by-pass with the result that the pressure or fluid within said chamber is also varied for effecting the desired pitch of the fan blades.
